UNITED STATES PATENT OFFICE.

HAZEN PRESCOTT HUNTOON, OF BOSTON, MASSACHUSETTS.

COLLAR AND CRAVAT.

SPECIFICATION forming part of Letters Patent No. 327,687, dated October 6, 1885.

Application filed June 23, 1884. Serial No. 136,314. (No model.)

To all whom it may concern:

Be it known that I, HAZEN P. HUNTOON, a citizen of the United States, residing at Boston, in the county of Suffolk and State of Massachusetts, have invented an Improvement in Collars and Cravats for Personal Wear, of which the following is a specification.

My invention relates to collars and cravats for personal wear; and it consists of a collar 10 provided with button or eyelet holes, said button or eyelet holes being placed near or at the front part of the collar in a manner to receive buttons or othersuitable devices, which are secured to the cravat in positions corresponding to the positions of the button or eyelet holes in the collar.

The object of this invention is to provide means for the adjustment and retention of the cravat upon the person of the wearer.

20 In the accompanying drawings, Figure 1 is a view of a collar, showing the position of the button or eyelet holes. Fig. 2 is also a view of a collar, showing the position of the button or eyelet holes; and Fig. 3 is a back view of 25 a bow or cravat, showing the position of the buttons.

Similar letters refer to similar parts in each drawing.

In carrying out this invention, in addition 30 to the button-holes with which collars are usually provided, I provide the button-holes A A, Figs. 1 and 2, near the front part of the collar, which button-holes are for the purpose of receiving the buttons that are suitably placed 35 and secured upon the bow or cravat, and shown at B B, Fig. 3. In Fig. 1 the button-holes are represented as being in the flexible or turned-down portion of the collar, while in Fig. 2 the button-holes are represented as 40 being in the band portion of the collar. Either

or both plans may be employed, as the style of the collar may seem to require.

By this mode of adjustment the cravat or bow is adjusted or removed in a very brief space of time, and with little trouble, while it 45 is secured in a manner to relieve the wearer of much annoyance incident to the accidental disarrangement of the cravat or bow.

Buttons of any common style may be used on the cravat, or the ordinary lever or separable collar-buttons may be used. Eyelet-holes instead of button-holes, as shown, may sometimes be used in the collars, especially when the round-shank separable buttons are used. Hooks or wires may in some cases be 55 secured to the cravat or bow, and used in connection with eyelet or button holes.

When the cravat or bow is designed to be worn so as to be upon the outside of the collar, as in Fig. 3, the buttons will be placed 60 upon the inside of the cravat or bow; but when it is intended to wear the cravat or bow beneath the flexible or turned-down portion of the collar, it would be necessary to have the buttons on the outside of the cravat 65 or bow.

I claim—

The combination of a collar provided with a collar-band and flexible portion of ordinary construction, and having the button-holes A 70 A set equidistant from the front opening of collar, as described, with a cravat having buttons set thereon at points to permit their engagement with the button-holes in the collar, as set forth.

HAZEN PRESCOTT HUNTOON.
